FILING DRAWER

Frederick L. G. Straubel, Green Bay, Wis., assignor of one-eighth to O. C. Straubel, Green Bay, Wis., and two-eighths to C. W. Straubel, Youngstown, Ohio

Application August 3, 1931, Serial No. 554,605

6 Claims. (Cl. 129—26)

This invention relates to vertical filing drawers, more particularly to those having a tiltable front with reciprocating tilting follower.

The invention contemplates improvements and changes in the construction shown in my Patent No. 1,892,020, dated December 27, 1932.

The object of this invention is the provision of improved means connecting the front of the drawer with a follower positioned in the drawer whereby the tilting of the front end forwardly from its vertical position, causes a backward tilting of the follower and the returning of the front end also returning the follower to a vertical position.

15 As in my patent above referred to, the follower is locked in its upright position and is actuated only to an inclined position by the tilting of the front end. In operation the tilted follower also moves back at its base to allow for the loosening 20 of the contents at the bottom of the file.

The improvement mainly consists of a rearrangement of operating devices whereby better lifting facilities are provided to the follower in bringing it to an upright position with all or part 25 of the contents filed, bearing against it when in an inclined or tilted position.

With this object in view the invention consists in construction substantially as herein described and claimed and as set out in the accompanying 30 drawings of which:

Figure 1 is a longitudinal sectional view of the improved device with the parts arranged to hold the filed contents in a closed or vertical position.

Figure 2 is a cross section rear view of the file 35 drawer at line 2—2 of Figure 1.

Figure 3 is a view similar to figure 1 but showing the parts in open position to facilitate the filing of or reference to the drawer contents.

In the drawings Figures 1 and 3, the inner left 40 hand sides of the drawer are shown with the mechanical devices attached. In Figure 2 a sectional view of the main body is shown comprising the two sides and bottom of the file with provision for the sliding or movable follower at the 45 two lower corners. The means provided for the expanding operation, that is the tilting drawer front and the reciprocating tilting follower, are designated by the numerals hereinafter described, and while the means described is shown as 50 located at one side of the drawer, nevertheless it will be understood that the said means consists of complete sets of levers and links at opposite sides of the drawer. The drawer front 1 is hinged at its lower part at 2 to the 55 drawer bottom. The wing 3 provides a suitable

enclosure when the file is open and to which the link 4 is pivotally attached. Pivotally connected to link 4 are lever 5 and link 6. The plate 7 which is attached to the drawer side, has the lever 5 pivotally attached to it at 8 and the link 6 is 60 pivotally connected to the side member 9, the combination of levers and links thus formed actuate the side member 9 as the drawer front is tilted outward and brought back to an upright position. The side members 9 have longitudinal 65 dove tail formed grooves 10 to engage the flanged rollers 11 attached to brackets 12 extending rearwardly from the follower plate 13. The side member 9 with the oscillating links 14, 15 and 16 70 pivotally attached thereto at their upper ends and the same links pivotally attached at their lower ends to the stationary side member 17, gives the side member 9 a parallel rocking motion, backward and downward, as the drawer front is drawn or tilted outward as in Figure 3, 75 instead of backward and upward as described in my Patent No. 1,892,020.

As a means to hold the side member 9 in its upward position the coil spring 18 is attached at its lower end to the plate 7 and at its upper 80 end to the side member 9. In a closed or upright position the front 1 and the follower 13 are firmly held as provided by the tension of the spring 18 with the links 14, 15 and 16 vertically as in Figure 1. The rearwardly extending 85 brackets 12, when the follower 13 is tilted backward as in Figure 3, provide improved lifting power to the follower in bringing it to an upright position by the operation of the drawer front. 90

Instead of the usual follower slide in the center channel 18½ to have it free of obstructions, side follower slides 19 suitably recessed within the lower parts of the drawer sides, are provided as shown in Figure 2. These slides are attached 95 to the follower base 20 to which is hinged at 21 the follower blade 13.

Longitudinally along the bottom of the center channel 18½ are perforations suitably spaced to receive the projecting lug 22 of the sliding spring- 100 actuated member 23.

The lifting of the member 23 at its upper end will permit of moving the follower back and forth for adjustment in accordance with the contents filed and to be set in a perforation at a more 105 suitable point.

As the pivotal point of the tilting follower is at the lower end of the member 23 where the lug 22 enters a perforation within the drawer channel 18½, the follower base 20 will move back- 110

ward a distance corresponding with the elevation of the drawer bottom above the channel bottom and thereby loosen up the contents filed at the drawer bottom when the file is opened.

5 Having thus described my invention that which I claim to be new and desire to secure by Letters Patent is:

1. A filing drawer having a tiltable front and a tiltable follower provided with their axes of rotation beneath the bottom of the drawer, channel members located at opposite sides of the follower, brackets carried by the rear of the follower and having means for slidably engaging within said channel members, pivoted links for connecting said channel members with the lower portion of the drawer, springs for tensioning said channel members toward the drawer front, a pair of link members respectively connected with the drawer front and with each channel member, said link members being connected by intermediate levers pivotally supported at intermediate points on fixed parts of the drawer whereby outward movement of the drawer front will cause the channel members to move downwardly, and vice versa.

2. A drawer having an outwardly tiltable front and a rearwardly tiltable follower arranged in spaced-apart relation, follower-actuating members arranged at the sides of the drawer and having channel portions, brackets carried by the rear of the follower and having means for engaging in the channel portions of said follower-actuating members, links pivotally mounted at the lower portions of the sides of the drawer and having their upper ends pivotally connected with and supporting said members, fixed plates carried by the sides of the drawer, a link connected with the front end of each follower-actuating member, levers pivotally connected to said fixed plates and also pivotally connected to said second mentioned links, and other link members pivotally connecting the upper ends of said levers and the drawer front.

3. A drawer having a tiltable drawer front, a tiltable follower, grooved members on each side

of the drawer between the front and the follower, means on the back of the follower operatively engaging the grooves in said members, means for rockably mounting said members at the sides of the drawer, connections between said members and the drawer front, and springs each having one end anchored to a fixed drawer part and each having its other end connected to said grooved members.

4. In a filing drawer having a tiltable front and a tiltable follower provided with axes of rotation beneath the bottom of the drawer, means for actuating said front and follower comprising a pair of members, means for connecting said members with the rear side of the follower, pivoted means for supporting said members with respect to the drawer, pivoted levers connected with fixed drawer parts, and a plurality of links for respectively connecting said members with the levers and connecting the latter with the drawer front.

5. A drawer having a tiltable front and a tiltable follower, actuating members therefor, pivoted means supported from the drawer sides and connected with said members, links respectively connected with the drawer front and said actuating members, levers having fixed axes and having their ends connected with said links, and springs each having one end anchored to a fixed drawer part and each having its other end connected to one of said actuating members.

6. In a filing drawer the combination of a tiltable front pivoted in a fixed position beneath the bottom of the drawer and a tiltable follower, means for slidably and pivotally mounting the follower beneath the bottom of the drawer, follower-actuating members slidably connected with the rear side of the follower, a plurality of links respectively pivoted to the lower side of the follower actuating members and to the lower part of the sides of the drawer, and lever and link means operatively connecting said members with the tilting front.
